[57] CLAIM

The ornament design for a long neck bottle carton, as shown and described.

DESCRIPTION

FIG. 1 is a perspective view of a long neck bottle carton showing our new design, the broken line showing of a pair of end bottles is for illustrative purposes only and forms no part of the claimed design;

FIG. 2 is a top plan view thereof;

FIG. 3 is a front elevational view thereof;

FIG. 4 is a rear elevational view thereof;

FIG. 5 is a right side elevational view thereof, the left side elevational view being a mirror image thereof;

FIG. 6 is a bottom plan view thereof;

FIG. 7 is a top plan view of the long neck bottle carton in unassembled condition, the bottom plan view being a mirror image thereof;

FIG. 8 is a front elevational view of FIG. 7, the rear elevational view being a mirror image thereof; and,

FIG. 9 is a left side elevational view of FIG. 7; FIGS. 6-9 are on a reduced scale.

The dash lines and phantom lines shown on FIGS. 1, 2, 4, 6 and 7 represent tear lines and fold lines respectively.
